CLAIM

The ornamental design for a heat resistant cover, as shown and described.

DESCRIPTION

FIG. 1 is a top front perspective view of an embodiment of a heat resistant cover, illustrating the heat resistant cover opened;

FIG. 2 is a top front perspective view of the heat resistant cover shown in FIG. 1;

FIG. 3 is a top view of the heat resistant cover shown in FIG. 1;

FIG. 4 is a bottom view of the heat resistant cover shown in FIG. 1;

FIG. 5 is a left side view of the heat resistant cover shown in FIG. 1;

FIG. 6 is a right side view of the heat resistant cover shown in FIG. 1;

FIG. 7 is a front view of the heat resistant cover shown in FIG. 1;

FIG. 8 is a rear view of the heat resistant cover shown in FIG. 1;

FIG. 9 is a top front perspective view of another embodiment of a heat resistant cover, illustrating the heat resistant cover opened;

FIG. 10 is a top front perspective view of the heat resistant cover shown in FIG. 9;

FIG. 11 is a top view of the heat resistant cover shown in FIG. 9;

FIG. 12 is a bottom view of the heat resistant cover shown in FIG. 9;

FIG. 13 is a left side view of the heat resistant cover shown in FIG. 9;

FIG. 14 is a right side view of the heat resistant cover shown in FIG. 9;

FIG. 15 is a front view of the heat resistant cover shown in FIG. 9; and,

FIG. 16 is a rear view of the heat resistant cover shown in FIG. 9.

The dashed broken lines designate quilting or sewn lines of the article. The dash-dot-dot broken lines are shown for the purpose of illustrating parts of the article that form no part of the claimed design.

1 Claim, 16 Drawing Sheets
